UNITED STATES PATENT OFFICE.

HARRY W. YOUNG, OF WHITEHALL, MICHIGAN.

CHOCK.

1,291,341.

Specification of Letters Patent.

Patented Jan. 14, 1919.

Application filed April 30, 1917, Serial No. 165,469. Renewed April 27, 1918. Serial No. 231,277.

To all whom it may concern:

Be it known that I, HARRY W. YOUNG, a citizen of the United States, residing at Whitehall, in the county of Muskegon and 5 State of Michigan, have invented new and useful Improvements in Chocks, of which the following is a specification.

This invention relates to devices fastened to the deck of a vessel and having jaws between which a cable, hawser or the like is 10 adapted to be passed.

The invention has for its object to provide a novel and improved device of the kind stated, and one with which is combined a 15 flagstaff holder as will appear more fully hereinafter.

In order that the invention may be better understood, reference is had to the accompanying drawings forming a part of this 20 specification.

In the drawings,

Figure 1 is a perspective view showing one embodiment of the invention;

Fig. 2 is an elevation thereof;

Fig. 3 is a central vertical section;

Fig. 4 is a perspective view showing another embodiment of the invention;

Fig. 5 is a central vertical section of the structure shown in Fig. 4, and

Fig. 6 is a perspective view of a combined 30 railing stanchion and flagstaff holder.

Referring specifically to the drawings, 10 denotes the bow of a vessel, on which are mounted two chocks 11 and 12, respectively, 35 the same being metal blocks having jaws between which a cable, hawser, or the like is adapted to be passed. The two chock blocks are joined at one end and extend divergently therefrom to run parallel to the 40 sides of the vessel. The outer ends of the chock blocks are apertured for fasteners 13 whereby they are secured at these ends to the deck or other part of the vessel. The inner or meeting ends of the chock blocks are provided with matching hinge knuckles, the 45 knuckles of the block 11 being shown at 11^a. The block 12 has a single knuckle 12^a seating between the knuckles 11^a. The knuckles have alined apertures to receive a standard 50 or stanchion 14 which is hollow, thus forming a socket into which a flag staff 15 may be inserted and held, as shown in Fig. 1. The bottom end of the stanchion is closed 55 and fastened down to the deck or other part of the vessel by a screw or other suitable

means 16 passing through said end as shown in Fig. 3.

Before applying the fasteners 13, the blocks 11 and 12 are set at the desired angle, and they are held stationary upon applying 60 said fasteners. The stanchion 14 passing through the knuckles of the blocks provides a pivotal connection therebetween, thus enabling them to be readily set at the desired angle.

The stanchion 14 is tapered toward the bottom so that when the fastener 16 is applied, it is wedged tightly in the alined apertures of the hinge knuckles 11^a and 12^a, and the chock blocks are firmly secured to successfully withstand the strain to which they are subjected when in use.

In Figs. 4 and 5 are shown two chock blocks 17 and 18, respectively, also pivotally connected at one end and extending divergently therefrom, with their outer ends fastened down as shown at 16^a. The block 18 has a single hinge knuckle 18^a fitting between knuckles 17^a on the block 17. The top one of the knuckles 17^a is continued upward 75 to form a tubular stanchion 19 having at the top a side socket member 19^a. On top of the stanchion seats a ring 20 having a side socket member 20^a lying in a common plane with the socket member 19^a. The ring 20 may be 80 rotated to place the socket members 19^a and 20^a divergently at any desired angle, and as the socket members are designed to receive the horizontal rods or bars of a railing, it 85 will be seen that the latter is readily adjustable to extend parallel to the sides of the vessel.

The stanchion 19 is hollow and receives a flagstaff holder 21 similar to the holder 14 hereinbefore described, said holder also passing through the ring 20, and thus holding the latter to the stanchion.

Fig. 6 shows a combined flagstaff holder and railing support. This device comprises a flat base 22 from which rises a hollow 100 standard 23 on top of which seats a ring 24. The ring 24 and the top of the standard 23 have socket members 25 and 26, respectively, similar to the members 19^a and 20^a, and for the same purpose.

The standard 23 is hollow to receive a flagstaff holder 27. The device is secured to the deck or other part of the vessel by fasteners passing through apertures in the base 22.

110

I claim:—

1. The combination of a pair of chocks having hinge knuckles at one end and extending divergently therefrom, said knuckles being provided with alined apertures, a retaining member passing through the knuckle apertures, and securing means for the outer ends of the chocks.
2. The combination of a pair of chocks having hinge knuckles at one end and extending divergently therefrom, said knuckles being provided with alined apertures, a socketed retaining member passing through the knuckle apertures, and securing means for the outer ends of the chocks.
3. The combination of a pair of chocks having hinge knuckles at one end and extending divergently therefrom, said knuckles being provided with alined apertures, the top one of the knuckles having an upward tubular extension, a ring seating on top of the extension, side socket members on the ring and the extension, a retaining member passing through the ring, the knuckle extension and the knuckle apertures.
4. The combination of a pair of chocks

having hinge knuckles at one end and extending divergently therefrom, said knuckles being provided with alined apertures, the top one of the knuckles having an upward tubular extension, a ring seating on top of the extension, side socket members on the ring and the extension, a retaining member passing through the ring, the knuckle extension and the knuckle apertures, said retaining member being tubular, and a socket member seating in the retaining member.

5. The combination of a tubular standard, a ring seating on top of the standard, a retaining member passing into the standard and through the ring, and side socket members on the standard and the ring and lying in a common plane.

6. The combination of a tubular standard, a ring seating on top of the standard, a socketed retaining member passing into the standard and through the ring, and side socket members on the standard and the ring and lying in a common plane.

In testimony whereof I affix my signature.

HARRY W. YOUNG.
